MULTIPLE UNIT HOUSING STRUCTURE

Louis J. Jenn, 4917 Laurel Circle,
Indianapolis, Ind. 46226

Original design application July 15, 1968, Ser. No. 12,739,
now Patent No. 216,954, dated Mar. 24, 1970. Divided
and this application Nov. 13, 1969, Ser. No. 20,056

Term of patent 14 years

Int. Cl. D25—04

U.S. Cl. D13—1

FIG. 1 is a perspective view of a multiple unit housing structure according to my design.

FIG. 2 is a side elevation of the structure shown in FIG. 1.

FIG. 3 is a partial perspective view similar to FIG. 1. The sides of the structure not shown in FIG. 1 are similar to the sides which are shown.

This is a division of application Ser. No. D. 12,739 filed July 15, 1968, now Pat. No. D. 216,954.

I claim:

The ornamental design for a multiple unit housing structure, as shown and described.
